BOOK

Arthur F. Brock, Madison, N. J.

Application June 6, 1941, Serial No. 396,789

6 Claims. (Cl. 281—19)

The invention herein disclosed relates particularly to books of the mechanically bound type, in which the leaves are held in a mechanical form of binding, usually of wire, sheet metal or plastic. Such bindings have the advantages of complete reversibility and free swinging of the leaves over from one side to the other.

Important objects of the present invention are to provide a cover construction for bindings of the type mentioned and simple and inexpensive means for securing the bound leaves in the cover and which while holding the leaves properly centered, will not interfere at all in the free swinging and reversing movements of the leaves.

Also it is a purpose of the invention to secure the bound sheets in place in a manner that will not add to the bulk of the book or interfere with the flexibility of the covers or the bound sheets, which will be unobtrusive and practically invisible in the ordinary use of the book and which will provide a particularly practical and effective construction for books of the refillable type.

Other desirable objects and the novel features by which purposes of the invention are attained will be in part apparent from or are set forth in detail in the course of the following specification.

The drawing accompanying and forming part of the specification illustrates simple commercial embodiments of the invention. Structure however may be modified and changed as regards this disclosure all within the true intent and broad scope of the invention as hereinafter defined and claimed.

Fig. 1 is a broken plan view showing the invention applied to a book of the refill type, the book appearing in open position with the sheets all turned over on the front cover.

Fig. 2 is an enlarged broken sectional detail as on line 2—2 of Fig. 1.

Fig. 3 is an end view of the book with the cover closed position.

Fig. 4 is a broken detail illustrating a simple way of engaging a refill in or removing it from the cover.

Fig. 5 is a broken detail view of a modification.

The invention is particularly adapted to and is here illustrated in conjunction with a binding of the "Wire-O" type, in which the sheets 5, perforated at 6, are held by a single continuous wire, bent in zig-zag fashion into the form of doubled hooks or rings 7, connected at the back in spaced parallel relationship by short straight intermediate connecting portions 8.

A special feature of the present invention is the utilization of these short flexibly related,

longitudinally extending back connections as a part of the means for retaining the binding in the cover structure.

In the illustration, the cover is made up of front and back cover sections 9, 10, flexibly connected by a back portion 11.

Mounted on the back 11, between the cover hinging edges 12, 13, are two or more transversely extending retaining hooks 14, spaced to engage over two or more of the longitudinally extending back connections 8, of the binding.

In the present illustration, two such transversely extending retainers are provided, one near the top and the other near the bottom of the back and spaced to engage the sides of the adjoining rings at 15, thus to hold the binder snugly against longitudinal shifting movement in the cover.

In a preferred form of construction, the retainers 14, are formed as projecting spring tongues struck up from the edge portions of tubular rivets 16, set in the back, said spring tongues having at the base of the same substantially circular wire clasping portions 17, approximately at the edges of the eyelets and extending inward toward or into the tubular structure of the eyelets at 18, and terminating in outwardly inclined cam portions 19.

The rounded portions 17, at the root ends of the holding tongues may be only slightly larger than the cross-section of the wire, so as to form loose bearings for the back connections 8, the inwardly extending portions 18, serve as retaining means to hold the back connections in such bearings and the outwardly inclined tips 19, may be used as cams to lift the spring tongues under pressure of the back connections when entering the binder in the cover. In similar manner, the inwardly inclined portions of the tongues ad-joining the more or less circular retainer portions may serve as cams to force the spring tongues open, in releasing a binding from the cover.

The eyelet or rivet form of base structure for the spring holding tongues takes up little space and does not impair or interfere with the flexure of the back or cover sections. The illustration shows how these hooks may be so small as to occupy only the space between two of the adjoining rings of the binder and thus be out of the way, so as not to interfere with free turning of the sheets and practically hidden at the back of the binder.

The longitudinal connecting portions of the binding may be used as wedges to force open the

retainers in placing or removing the refills and, as shown in Fig. 4, the parts may be engaged or disengaged one at a time. Thus in the view referred to, the connection portion of the binder has been engaged or is still engaged with the retainer at the top, while the connecting portion at the bottom has been released from or is not yet engaged with the lower retainer, the binding being at an inclined relation, hinging on the top retainer to swing it into or free it from engagement with the other retainer.

While retainers at the top and bottom usually are sufficient, for longer books, one or more intermediate retainers may be provided, it only being necessary that these be located so as to catch one or more of the longitudinal portions connecting the rings in the intermediate section of the binding.

The connecting portions form in effect a flexible backbone and the engagement of the retainers with these flexibly joined back connections does not destroy or impair the desired flexible character of the binding or cover structure. The end retainers by engagement with the inner sides of the end hooks or rings hold the binding in its normal longitudinally distended condition. The engagement and disengagement is effected by a short substantially transverse relative movement of the parts, which requires no bending or mis-shaping of either the binding, the sheets or the cover structure.

While the invention is of particular value as a refillable book construction, it is realized that the hooks or holding tongues may be wholly or permanently closed about the back connections of the binding, thus to permanently secure the bound sheets within the cover structure. It is realized also that the binder rings may not be entirely closed, thus to leave the sheets in a removable and replaceable relation, held for example, by special retaining means, such as covered in patent application Ser. No. 379,571, filed February 19, 1941.

Fig. 5 shows how the retainers may be made with the retaining loops or bearings 17a, located substantially centrally over the eyelet bases, thus to hold the binding at all times substantially at the center of the book, directly over the rivets. In this, as in the first form of construction, the transversely extending spring tongue has an upwardly or outwardly inclined cam portion 19a, for wedging engagement by a connecting bar 8, and a downwardly or inwardly inclined cam portion 18a, for facilitating the releasing action of the spring holding tongue.

What is claimed is:

1. In a book having a filler bound together with a wire bent zig-zag into doubled rings connected in spaced parallel relation by short substantially straight longitudinally extending portions and a cover having front and back cover sections hingedly connected by a back, retaining means comprising tubular rivets fastened through said back and spring fingers integral with said rivets bent over the faces of the rivets at the inside of the back and having loops rotatably receiving longitudinally extending short connecting portions of the binding and end portions inclined in relation to the inside faces of said rivets.

2. In a book construction for perforated sheets bound together by spaced substantially parallel rings connected in such spaced relation by short intermediate longitudinally extending connections and comprising a cover with a back por-

tion, bases in spaced relation near the upper and lower ends of said back portion, transversely extending spring securing tongues overstanding said bases and connected to said bases by rounded portions forming bearings receiving longitudinally extending connections of the binding, said tongues having portions extending toward said bases to retain said connections and having end terminals inclined away from said bases to serve as cams opposed to said bases for reception of said connections between said bases and terminal ends of said fingers.

3. In a book construction for perforated sheets bound together by spaced substantially parallel transverse rings connected in such spaced relation by short intermediate longitudinally extending connections and comprising a cover with a back portion, bases in spaced relation near the upper and lower ends of said back portion, transversely extending spring securing tongues overstanding said bases and connected to said bases by rounded portions forming bearings receiving longitudinally extending connections of the binding, said tongues having portions extending toward said bases to retain said connections and having end terminals inclined away from said bases to serve as cams opposed to said bases for reception of said connections between said bases and terminal ends of said fingers, said transversely extending tongues engaging the inner edges of transverse rings at the outer ends of the connections retained by said transverse fingers.

4. A book structure for a binding of the type having transversely disposed spaced parallel binder rings connected at the back in such spaced relation by short longitudinally extending connecting portions and comprising in combination with a back structure, bases secured in widely spaced relation on said back structure to register with the spaces between adjoining rings and spring retaining fingers overstanding and carried by said bases and projecting transversely of the back structure in positions to register with and engage about longitudinally extending short connecting portions at the back of the binding, said retaining fingers having arched portions partially surrounding said connecting portions of the binding, inclined portions extending from said arched portions toward said bases and end portions inclined away from said bases.

5. A book structure for a binding of the type having transversely disposed spaced parallel binder rings connected at the back in such spaced relation by short longitudinally extending connecting portions and comprising in combination with a back structure, bases secured in widely spaced relation on said back structure to register with the spaces between adjoining rings and spring retaining fingers overstanding and carried by said bases and projecting transversely of the back structure in positions to register with and engage about longitudinally extending short connecting portions at the back of the binding, said retaining fingers having arched portions partially surrounding said connecting portions of the binding, inclined portions extending from said arched portions toward said bases and end portions inclined away from said bases, said arched portions being located toward one edge of said bases.

6. A book structure for a binding of the type having transversely disposed spaced parallel binder rings connected at the back in such spaced relation by short longitudinally extending connecting portions and comprising in combina-

tion with a back structure, bases secured in widely spaced relation on said back structure to register with the spaces between adjoining rings and spring retaining fingers overstanding and carried by said bases and projecting transversely of the back structure in positions to register with and engage about longitudinally extending short connecting portions at the back of the binding,

said retaining fingers having arched portions partially surrounding said connecting portions of the binding, inclined portions extending from said arched portions toward said bases and end portions inclined away from said bases, said arched portions being located substantially over the center of said bases.
